(57) **CLAIM**

The ornamental design for a wind-powered fishing pole, as shown and described.

DESCRIPTION

FIG. 1 is a side elevational view illustrating an alternate embodiment of wind-powered fishing pole showing the new ornamental design;

FIG. 2 is a top plan view thereof;

FIG. 3 is a bottom plan view thereof;

FIG. 4 is a front elevational view thereof; and,

FIG. 5 is a rear elevational view thereof.

The details shown in broken lines in these Figures are shown for illustrative purposes only and form no part of the claimed design.
